POPCORN DISPLAY STAND

Harold J. Fitzgerald, Milwaukee, Wis., assignor to Supur-display, Inc., Milwaukee, Wis., a corporation of Wisconsin

Application August 15, 1955, Serial No. 37,462

Term of patent 14 years

(Cl. D80—11)

Fig. 1.

Fig. 2.

Fig. 3.

Fig. 4.

Fig. 5.

Fig. 1 is a view in perspective of a Popcorn Display Stand showing my new design.

Fig. 2 is a view in plan of the Popcorn Display Stand shown in Fig. 1.

Fig. 3 is a front view in elevation of the Popcorn Display Stand shown in Fig. 1.

Fig. 4 is a left end side view in elevation of the Popcorn Display Stand shown in Fig. 1, and

Fig. 5 is a rear perspective view taken from the left side of Fig. 1.

The characteristic feature of my design resides in the full line portions of the drawing.

I claim:

The ornamental design for a popcorn display stand, as shown and described.
